UNITED STATES PATENT OFFICE.

WILSON E. PORTER, OF NEW HAVEN, CONNECTICUT, ASSIGNEE TO NEW HAVEN CLOCK CO., OF NEW HAVEN, CONNECTICUT, A CORPORATION.

KEYLESS CLOCK.

979,797.

Specification of Letters Patent. Patented Dec. 27, 1910.

Application filed September 19, 1910. Serial No. 582,720.

To all whom it may concern:

Be it known that I, WILSON E. PORTER, a citizen of the United States, residing at New Haven, in the county of New Haven and State of Connecticut, have invented a new and useful Improvement in Keyless Clocks; and I do hereby declare the following, when taken in connection with the accompanying drawings and the letters of reference 10 marked thereon, to be a full, clear, and exact description of the same, and which said drawings constitute part of this specification, and represent, in—

Figure 1 a view in side elevation of an 15 automobile clock constructed in accordance with my invention. Fig. 2 a view thereof in rear elevation with a portion of the finger-button broken away. Fig. 3 a broken 20 view thereof in central vertical section, on an enlarged scale. Fig. 4 a perspective view of the clock proper, showing it detached from the supporting-disk and bracket upon which it is rotatably mounted. Fig. 5 a detached view in inside elevation of the 25 supporting-disk on which the clock-proper is rotatably mounted.

My invention relates to an improvement in keyless clocks of that class commonly known today as "automobile clocks," 30 though not limited to use on automobiles; the object being to produce at a low cost for manufacture, a simple, convenient and durable keyless clock constructed with particular reference to fewness of parts, non-liability 35 to derangement and smoothness of winding action.

With these ends in view, my invention consists in a keyless clock having certain 40 details of construction and combinations of parts as will be hereinafter described and pointed out in the claims.

In carrying out my invention as herein shown, I employ a cylindrical case 2 having its forward end externally threaded for the 45 reception of an internally threaded bezel 3 formed with an ornamental bead 4 and with an integral mat or reflector 5. A crystal 6 mounted in the bezel 3 protects the dial 7, which is applied to the outer face of a dial- 50 plate 8 carrying short spacing-pillars 9 by

which it is secured by nuts 10 to the front plate 11 of the clock-movement which also comprises intermediate movement-plates 12 and 13 and a rear movement-plate 14, the said movement-plates being secured together in proper relative positions in any suitable manner as by pillars 15. The clock-movement may be of any approved construction as to its train which it has seemed sufficient to designate by a single reference number 15^a.

Near its rear end the case 2 is provided with a disk-shaped fixed back 16 soldered or otherwise secured in place and having the clock-movement secured to it by short 65 spacing-pillars 17 which are riveted in the rear movement-plate 14 which receives screws 18 passing from rear to front through the said case-back 16 as clearly shown in Fig. 3, whereby the clock-movement is fastened to or organized with the case 2 so as to rotate therewith. The short spacing-pillars 17 establish between the rear movement-plate 14 and the case-back 16, a narrow 70 space 19 for the reception of the main winding-ratchet 20 of the clock-movement, this ratchet being fixed upon the main winding-arbor 21 which extends forward through the rear movement-plate 14 in which it has bearing and through the spring-barrel 22 75 and is formed at its forward end with a trunnion 23 bearing in the middle of the intermediate movement-plate 13. The said arbor 21 is formed with a hub 24 to which the inner end of the main-spring 25 is secured in the ordinary manner, the outer end of the said spring being attached to the periphery of the said spring-barrel. Near its 80 extreme forward end the arbor 21 is formed with a shoulder 26 forming a bearing for 85 the main-wheel 27 to which the spring-barrel 22 is secured, the said wheel 27 rotating upon the shoulder 26 which remains at rest. The arbor is also formed with a shoulder 28 passing through the center of a disk-shaped plate 29 employed to close the spring-barrel 22. A pawl 20^a pivotally mounted upon the rear face of the rear movement-plate 14 and provided with a spring 30 and located within the space 19 aforesaid, en- 90 95 100

gages with the teeth of the ratchet-wheel 20 over which it is dragged, so to speak, while the clock-movement and its case 2 are being bodily rotated while the ratchet 20 and arbor 21 are at rest.

The clock-case 2 and therefore the clock-movement, are normally held against rotation by means of a coupling-pin 31 provided at its rear end with a knurled finger-button 32 and mounted for rotatable and longitudinal movement in a hub 33 fixed in a supporting-disk or plate 34 fitting within the rear edge of the case 2, and attached by screws 35 to a bracket 36 the perforated ears 37 of which project beyond the edge of the said disk 34 and are located in a plane at an angle to the plane thereof so that the clock will be supported in an inclined position as shown in Figs. 1 and 3, when it is to be used as an automobile clock. Of course the construction of the bracket 36 will depend upon the use to which the clock is to be put. The said plate 34 and bracket 36 constitute the clock-base or clock-supporting means and remain fixed while the clock is being rotated for the winding of its spring. At its extreme forward end the coupling-pin 31 is reduced in diameter to form a nose 38 adapted to enter a corresponding hole 39 in the outer face of the case-back 16. When the nose 38 is entered into the hole 39, the case 2 will be coupled to the plate 14 and the case and movement held against rotation. A spring 40 encircling the inner end of the pin 31, exerts a constant effort to hold the nose 38 in the hole 39, this spring being interposed between a stop-collar 41 mounted upon the pin 31 near the forward end thereof and an abutment 42 within the hub 33. For lifting the nose 38 out of the hole 39 and holding it in its retracted position, the outer end of the hub 33 is formed with a lifting-cam 43 which is engaged by a lifting-pin 44 mounted in the coupling-pin 31 and riding upon the surface of the cam 43. Preparatory to winding the main-spring 25, the finger-button 32 is grasped and turned from left to right, whereby the lifting-pin 44 rides over the lifting-cam 43 with the effect of retracting the coupling-pin 31 against the tension of the spring 40 and withdrawing the coupling-nose 38 from the hole 39, leaving the clock-movement and the case 2 free to be bodily rotated with respect to the main winding-arbor 21 and the clock-base, consisting, as shown, of the plate 34 and the bracket 36, the pin 31 being maintained in its retracted position by the riding of the lifting-pin 44 up over the cam 43 out onto the level outer edge of the hub 33. After the main-spring 25 has been wound, the finger-button 32 is turned in either direction until the lifting-pin 44 is brought

into registration with some part of the cam 43. Now, when in the rotation of the case-back 16 with the case 2, the hole 39 is brought into registration with the nose 38, the spring 40 will at once act to push the coupling-pin 31 forward and enter its nose 38 into the hole 39, whereby the clock-case 2 will be again coupled with the clock-base and held against rotation.

Inasmuch as in my improved construction, the clock-movement is itself rotated, its dial 7 must also be rotated with it. This makes it necessary to provide for resetting the dial, so to speak, in an upright position after the spring has been wound, that is, with the "12" on the dial, uppermost. For this purpose I employ, as herein shown, a dial-resetting ratchet 45 located within a narrow space 46 formed between the case-back 16 and the supporting-plate 34 by the interposition between them of a spacing-ring 47 or some equivalent thereof, the said ratchet 45 being formed with a shoulder 48 bearing in an opening 49 in the center of the supporting-plate 34. The said ratchet 45 is formed with a square central opening 50 for the reception of the squared outer end of the main-winding arbor 21 with which the ratchet 45 rotates from right to left when the dial is being reset, but at no other time. A pawl 51 pivotally mounted upon the front face of the supporting plate 34 and provided with a spring 52 coacts with the ratchet 45 and prevents the arbor 21 from turning from left to right.

When the clock-case 2 and the clock-movement are being bodily turned from left to right for the purpose of winding the main-spring 25, the main-arbor 21 and the ratchet-wheels 20 and 45 remain at rest, the arbor being held against rotation by means of the engagement of the pawl 51 with the ratchet 45, while the pawl 29 of the main-ratchet 20 is being trailed over the teeth of the same, since the said pawl 29 is carried by the rear movement-plate 14 which is revolved as a part of the clock-movement. This provides for the winding of the clock. When the clock has been wound, it still remains necessary to reset the dial 7 so as to properly position its figure 12, since the chance of the figure 12 on the dial being in its proper uppermost position at the conclusion of the operation of winding the clock, would be only a remote chance. The resetting of the dial is done by bodily turning the clock from right to left for the required distance which will always be less than one entire revolution. During this reverse movement of the clock for the purpose of resetting the dial, the arbor 21 will rotate from right to left, and turn both of the ratchet-wheels 20 and 45, the pawl 29 of the ratchet-wheel 20 being engaged with the same while the ratchet-wheel 45 rides

under the pawl 51 carried by the supporting plate 34. The turning of the clock proper from left to right for the purpose of winding the main-spring 25, is of course done 5 against the tension of the main-spring, but the turning of the clock from right to left for resetting the dial, is done only against the tension of the pawl-spring 52.

The organization of parts forming the 10 clock proper, (the clock-case 2 and the clock-movement), are coupled to the clock-base (the plate 44 and the bracket 36) by the passage of the rear end of the main winding-arbor 21 through a washer 53 set into an 15 opening 54 in the bracket 36, the projecting rear end of the arbor receiving a fastening-pin 55 the removal of which enables the clock proper to be removed as shown in Fig. 4.

20 It will be seen from the foregoing that in my improved keyless clock, the clock-movement and its case are bodily rotated for winding the main-spring, while the main winding arbor remains at rest, whereby I 25 dispense with the use of the gears necessary in keyless clocks employing bezels or shells for winding the spring.

I claim:-

1. In a keyless clock, the combination with 30 a clock-base or supporting means, of a clock-movement bodily rotatable in either direction, and a winding-arbor coupling the said movement to the said base or supporting means, and held against rotation when the 35 movement is rotated for winding the clock but rotatable with the movement when the same is reversely rotated for resetting the dial.

2. In a keyless clock, the combination with 40 a clock-base or supporting means, of a clock-movement bodily rotatable in either direction, a winding-arbor coupling the movement to the said base or supporting means, and means for normally holding the winding arbor against rotation when the clock-movement is being bodily rotated for winding 45 the clock.

3. In a keyless clock, the combination with 50 a clock-base or supporting means, of a clock-movement, a case therefor, a winding-arbor coupling the said movement and case to the said base or supporting means, and means for normally holding the winding arbor against rotation when the clock-movement 55 and case are being bodily rotated for winding the clock, the movement and case being manually rotatable in one direction for winding the clock while the arbor remains at rest, and the arbor being rotated in the 60 opposite direction with the movement and case for resetting the clock-dial.

4. In a keyless clock, the combination with 65 a centrally arranged winding-arbor, of a movement rotatable with respect to the said

arbor, a ratchet-wheel located upon the 65 arbor, a pawl carried by the movement and coacting with the said ratchet-wheel over which it sweeps, means for supporting the said movement, a dial-resetting ratchet-wheel mounted upon the arbor for rotation 70 therewith, and a pawl coacting with the ratchet-wheel last mentioned and connected with the said supporting means, whereby the main-spring is wound by rotating the movement in one direction while the arbor 75 remains at rest, and whereby the dial is reset by rotating the movement in the other direction and rotating the arbor with it.

5. In a keyless clock, the combination with 80 a centrally arranged winding-arbor, of a movement rotatable with respect to the said arbor, a ratchet-wheel fixed upon the said arbor, a pawl carried by the said movement and coacting with the said ratchet-wheel over which it sweeps when the movement is 85 being rotated, means for supporting the said movement, a dial-resetting ratchet-wheel mounted upon the arbor for rotation therewith, and a pawl coacting with the ratchet-wheel last mentioned and connected with the 90 said supporting means, whereby the main-spring of the said movement is wound by rotating the movement in one direction while the arbor remains at rest, and whereby the dial is reset by rotating the movement in the 95 other direction and rotating the arbor with it, the said movement being connected with the said supporting means through the medium of the arbor.

6. In a keyless clock, the combination with 100 a clock-case, of a movement located therein, a case-back fixed within the case and having the movement secured to it, a bracket, a disk-shaped supporting-plate secured to the bracket and fitting within the rear end of 105 the clock-case, a winding-arbor extending rearward from the movement and passing through the said supporting-plate, a ratchet-wheel fixed upon the said winding-arbor, a pawl connected with the said movement for 110 engagement with the said ratchet-wheel, a dial-resetting ratchet-wheel non-rotatably mounted upon the said arbor, and a pawl carried by the said supporting-plate and engaging with the said dial-resetting ratchet-wheel, whereby the main-spring is wound by 115 turning the clock-movement and case in one direction with the arbor at rest and reset by turning them in the other direction, the arbor being then turned.

7. In a keyless clock, the combination with 120 a clock-base or supporting means, of a clock-movement and case rotatably connected with the clock-base and rotatable in one direction for winding the clock-spring, and in the opposite direction for setting the clock-dial, and means for normally holding the clock-case against rotation in either direction.

8. In a keyless clock, the combination with a clock-base or supporting means, of a clock-movement and case rotatably connected with the said clock-base and rotatable in one direction for winding the clock-spring and in the opposite direction for resetting the clock-dial, and means carried by the clock-case for coupling the same against rotation the said means comprising a longitudinally

movable and rotatable coupling-pin mounted in a cammed hub in the said clock-case.

In testimony whereof, I have signed this specification in the presence of two subscribing witnesses.

WILSON E. PORTER.
